DUMPING HOPPER

Albert E. Zimmer, Chicago, Ill., assignor to Enterprise Railway Equipment Company, Chicago, Ill., a corporation of Illinois

Application April 24, 1952, Serial No. 284,097

6 Claims. (Cl. 105—290)

This invention relates to an improved dumping hopper such as used in connection with a portable container or a dumping railway car and the like.

The objects of the invention, among others, are to provide improved mechanism for operating a pair of dumping doors which, when in closed position, meet in V-shaped relation; to provide for operating toggle locking mechanism connecting a pair of doors from a location adjacent the pivotal axis of one of the dumping doors; to provide mechanism which compensates for variations in the distance between the pivotal centers of a sprocket and chain connection extending between a dumping door and the hopper structure; to provide an improved lost motion safety clutch connection for a dump door mechanism; and more specifically, to provide an improved mechanism for operating a pair of swingingly mounted doors from a location adjacent the pivotal axis of one of the doors by means of a driving sprocket rotatably mounted on the hopper structure and operating to rotate an operating shaft carried by one of the doors.

The invention further resides in certain details of construction such as will be pointed out hereinafter.

For further comprehension of the invention, reference may be had to the accompanying drawings wherein:

Figure 1 is a vertical longitudinal side view of a container with the guard plate omitted, said container having a pair of dumping doors and the improvements of the present invention applied thereto, said view illustrating in full line the doors in closed position and the toggle locking mechanism in closed position and illustrating by conventional dot and dash lines the position of certain of the parts with the doors in opened position.

Figure 2 is a plan view of a portion of the operating mechanism shown in Figure 1.

Figure 3 is a sectional view at an enlarged scale taken generally along the line 3—3 of Figure 2.

Figure 4 is a vertical sectional view on an enlarged scale taken through the lost motion mechanism and on a line 4—4 of Figure 2.

Figure 5 is a modified embodiment of the invention showing a vertical sectional view taken through the lower portion of a railway dumping car, said view showing the doors in toggle locked position and indicating by conventional dot and dash lines the position of the doors when they are in opened position.

Figure 6 is a side longitudinal elevational view of the car structure shown in Figure 5 with a portion of the sill broken away to show the mechanism adjacent the operating end of the doors, said broken away section being taken on line 6—6 of Figure 5.

Figure 7 is a plan view of a portion of the structure shown in Figure 5 illustrating so much of the car as necessary to illustrate the mechanism in relation to the operating end of the doors.

Figure 8 is a fractional vertical transverse sectional view taken on a line 8—8 of Figure 7 and showing the locking pawl mechanism in locked position and illus-

2

trating the clutch segments in position with the mechanism locked.

Figure 9 is a fractional vertical sectional view similar to Figure 8, except that the locking pawl mechanism is shown in released position and the clutch mechanism in position with the lost motion taken up preparatory to releasing the mechanism.

Referring first to the construction shown in Figures 1 to 4, inclusive, the improvements are shown as embodied in a portable container having a four-sided hopper 100 with a supporting framework including a base portion formed of longitudinally extending beam members 101 united by transversely extending beam members 103 and 104, and extending vertically therefrom at the juncture of said longitudinal and transverse members are corner posts 105 of angular shape which are secured to said beam members at 106 and further braced thereto by diagonally disposed braces 107.

The hopper 100 is formed of sloping end walls 108 and 109 which connect with side walls 111 to form a foursided hopper leading to a foursided discharge opening 112. The respective end walls 108 and 109 are suitably reinforced by angle shaped members 113 which in turn are braced to the corner posts by means of diagonally extending braces 114. At the lower margin of each sloping end wall a reinforcing angle member 115 is provided, and secured thereto are hinge butts 116 for receiving pintles 117 for supporting dumping doors 118. The doors 118 are arranged to swing to closed position and meet in V-shaped relation.

The side walls 111 of the hopper 100 include substantially vertically disposed sections 119 which are spaced inwardly from the corner side posts 105 to form a space for housing door operating and retaining mechanisms as will be described hereinafter. The side walls 111 diverge outwardly at an angle from the vertical sections to present slopes 120 and thence extend upwardly to form attaching flanges 121. At the lower margins of the vertical sections 119 are Z-shaped reinforcements 122 against which the doors 118 bear when in closed position.

The doors 118 adjacent their swinging edges are reinforced by means of Z-shaped beam members 124, and co-acting with them at each end of the doors 118 is a toggle acting locking mechanism including a link 125 pivotally connected at one end at 125' to arm 126, the latter being rigidly connected to an operating shaft 127 which in turn is rotatably mounted in brackets 128 carried by the beam member 124 of the related door. The pivotal connection of link member 125 with the door 118 is carried out through the medium of an adjusting eyebolt 129 which is adjustably mounted on a bracket 130 carried by the beam member 124 of the door.

The toggle mechanism is of the jackknife type and is arranged to fold, as shown in Figure 1, when in operative locking position and is swingable through an arc of approximately 180 degrees to open position, the link 125 and arm 126 assuming a straight line position when the doors 118 are opened as shown by broken lines in Figure 1.

Operation of the toggle mechanism is effected by a link chain connection 131 operable through the medium of driven and driving sprockets 132 and 133 carried by the operating shaft 127 and the hopper framing, respectively. The operating sprocket 133 is pivotally mounted to rotate about an axis 134 disposed at one side of the pivotal axis 118' of the adjacent door 118 and consequently the axis 127 of shaft 127 swings on an arc 135 whereas a similar arc 136 swung on a radius from the axis 134 of sprocket 133 is of lesser length. The variation in the distances between the sprockets 132 and 133 brought about by the swinging movement of the door 118 is compensated for by disposing the contours of each of the sprockets 132

and 133 eccentrically with respect to the axes about which they rotate.

The driving sprocket wheel 133 is loosely mounted on an axle like hollow shaft member 137 to provide a limited degree of lost motion between it and its associated sprocket wheel 133. The shaft member 137 is rotatably mounted at its inner end on a bracket member 138 and the outer end is extended through a guard wall 139 and outwardly thereof is supported in a bearing 140. The outer end of the shaft member 137 outwardly of the bearing 140 is formed with a rectangular shaped section or operating head 141 for accommodating a wrench (not shown). Rigidly associated with the shaft 137 and preferably formed integrally therewith is a ratchet wheel 142 with which a locking pawl 143 cooperates to prevent reverse rotation of the shaft 137. The ratchet wheel 142, Figure 4, is formed with an annular section 144 having a segmental lug 145 adapted to engage with a segmental shaped extension 146 from the driving sprocket 133. The lug 145, during the opening operation of the doors 118, contacts the abutting surface 147 of the extension 146 and during the closing operation abutting surface 148 of the lug 145 engages the abutting surface 149 of extension 146 thereby allowing sufficient lost motion between the lug 145 and extension 146 as to permit the full sweep of the toggle mechanism independently of the rotating shaft 137. A locking dog 150 cooperates with the pawl 143 to lock the same in the position shown in Figure 1.

Referring now to the embodiment shown in Figures 5 to 8 inclusive, 200 and 201 indicate the longitudinal side sills of a railway car which carry door hinge brackets 202 for pivotally supporting at 203 dumping doors 204 and 205. The doors 204 and 205 are arranged to swing to closed position to meet in V-shaped relation and are retained in such position by toggle acting locking mechanism including an arm 206 and a link 207, the latter being pivoted at one end to door 205 at 208 and having the opposite end pivoted at 209 to the arm 206. The toggle mechanism is duplicated at each end of the doors 204 and 205 and in order to cause both mechanisms to function in unison the respective arms 206-206 are non-rotatably mounted on an operating shaft 210 which in turn is rotatably supported in bearings 211 carried by the door 205 along its swinging edge.

The doors 204 and 205 are suitably braced adjacent their swinging edges by beam members 212 and 213, the former forming a support for the brackets 211 and beam 213 having secured thereto brackets 214 which constitute the supporting means for adjusting screw threaded nuts 215 and complementary threaded eyebolts 216 whereby variations in the door closing relation may be effected, as will be understood.

Operation of the shaft 210 is preferably effected through the medium of sprocket and link chain connection including a sprocket wheel 217 non-rotatably mounted on an end of the shaft 210 and interconnected by a link chain 218 with another sprocket 219, the latter being mounted to rotate about an axis 219' stationarily disposed on the car structure. Rotation of the sprocket 219 is effected through the medium of a cross-shaft 220 which connects with the sprocket wheel 219 by means of a bevel gear 221 and bevel gear pinion 222, the latter being non-rotatably mounted on the cross-shaft 220 and the gear 221 having engagement with the sprocket wheel through the medium of a lost motion clutch connection, Figure 9, including interengaging segmental lugs 223 and 224 respectively movable in unison with the sprocket wheel 219 and the bevel gear 221. The sprocket wheel 219 is mounted loosely on a short hollow shaft 225 which in turn is mounted for rotation in bearing brackets 226 and 227 and integrally formed with hollow shaft 225 and disposed intermediate the bearing brackets 226 and 227 is a ratchet wheel 228 having an inner annular hollow portion 229 within which the segmental lug 223 of the

sprocket 219 is extended to co-act with the segmental lug 224 which latter is formed integrally with the inner face 230 of the hollow portion 229 of the ratchet wheel 228. The segmental lugs 223 and 224 together extend through an angular distance limited to provide a full half revolution of free movement of the sprocket wheel 219 and thereby provide for free rotary movement of the shaft 210 throughout the entire range of door opening movement. The bevel gear 221 is rigidly mounted on the outer end of the short shaft 225 and is secured in place by a rivet 231.

The mechanism is maintained against reverse rotation by means of a detent 232, Figure 8, which is pivotally mounted on the bracket 226 at 233 and it is biased by gravity to engage with the teeth of the ratchet wheel 228. The detent 232 is arranged for operation from either side of the car and to this end a cross-shaft 234 is provided and fitted with handles 235 at the ends. Rigidly mounted on the shaft 234 is a cam member 236 having oppositely disposed axially spaced cam sections 237 and 238 adapted respectively to engage the detent 232 on opposite sides of the detent pivot 233 to tilt it from operative latching position, Figure 8, to non-operative position, Figure 9, and vice versa.

25 The pivotal axis 219' of the sprocket wheel 19, as shown in Figure 5, is preferably disposed at a location spaced appreciably below the pivot 203 of the related door 205 which results in a variation in the distance between the pivotal axes of the respective sprocket wheels 217 and 219. To compensate for such variations these sprocket wheels are eccentrically mounted.

What is claimed as new is:

1. In a load containing hopper structure having a discharge opening and a pair of oppositely swinging doors 35 arranged to meet in V-shaped relation; toggle locking mechanism connecting the respective doors, said mechanism including a rotatably mounted arm journaled in one door and a link pivoted to the arm and to the companion door and disposed in toggle locked relation when 40 said doors are closed, means for rotating the arm including a driven sprocket wheel fixedly mounted in relation to the arm and a driving sprocket wheel rotatably mounted on the hopper structure at one side of the door hinge axis, and an endless chain trained over said sprocket 45 wheels whereby rotation of said driving sprocket wheel in either direction positively effects rotation of said driven sprocket wheel in the corresponding direction to operate said toggle locking mechanism from and to toggle locked position and to open and close said doors.

50 2. The structure, according to claim 1, wherein the contours of the sprocket wheels are eccentrically related to their respective pivotal axes to compensate for variations in the distance between sprocket wheel centers as the doors swing between open and closed positions.

55 3. The structure, according to claim 1, wherein a shaft having an operating head is rotatably supported on the hopper structure and wherein interengaging lugs are provided between said shaft and the driving sprocket wheel to provide full rotatable movement of the toggle mechanism independently of the operating head.

60 4. In a load containing hopper structure having a discharge opening and a pair of oppositely swinging doors for closing the opening, said doors when in closed position meeting in V-shaped relation, and toggle locking mechanism for retaining the doors in closed position including an arm pivoted to one door and a link pivoted to the opposite door and to the arm; means for rotating the arm including a driven sprocket fixed to the arm and a driving sprocket rotatably mounted on the hopper structure, an endless link belt connection trained over said sprockets whereby rotation of said driving sprocket in either direction positively effects rotation of said driven sprocket in the corresponding direction to operate said toggle locking mechanism from and to toggle locked 70 position and to open and close said doors, a shaft on which 75

the driving sprocket is rotatably mounted for limited rotary movement, a ratchet wheel rotatable with the shaft of the driving sprocket, said ratchet wheel having an annular ring portion and a segmental lug extending from the inner face of said annular portion inwardly towards the axis of the wheel, and a segmental lug on the driving sprocket, said segmental lugs on the ratchet wheel and sprocket being adapted to interengage to limit relative rotary movement between said shaft and driving sprocket.

5. The structure, according to claim 1, wherein a shaft extends transversely of the axis of the driving sprocket wheel, bevel gear drive means interconnects said shaft and said driving sprocket wheel, and a lost motion connection is interposed between said bevel gear drive means and said driving sprocket wheel to allow the latter to rotate independently of the former during opening movement of said doors.

6. The structure, according to claim 1, wherein a shaft extends transversely of the axis of the driving sprocket wheel, bevel gear drive means interconnects said shaft 20

and said driving sprocket wheel, a lost motion connection is interposed between said bevel gear drive means and said driving sprocket wheel to allow the latter to override the former during the opening operation of the doors, a ratchet wheel is rotatable in unison with said bevel gear drive means, a pivoted pawl engages said ratchet wheel, a cross-shaft extends transversely of said pivoted pawl, and cams extending in opposite directions from the axis of said cross-shaft are adapted alternately to engage with said pawl on opposite sides of its pivotal axis either to lock the same in locking engagement with said ratchet wheel or to move it to unlocked position.
